UNITED STATES PATENT OFFICE.

JOHN A. ALEXANDER AND FRANK K. BERRY, OF BATTLE CREEK, MICHIGAN, ASSIGNEES TO A. B. STOVE COMPANY, OF BATTLE CREEK, MICHIGAN, A CORPORATION OF MICHIGAN.

DESIGN FOR A STOVE-DOOR.

43,210.

Specification for Design.

Patented Nov. 5, 1912.

Application filed February 20, 1912. Serial No. 678,960. Term of patent 14 years.

To all whom it may concern:

Be it known that we, JOHN A. ALEXANDER and FRANK K. BERRY, citizens of the United States of America, residing at Battle Creek, in the county of Calhoun and State of Michigan, have invented a new, original, and ornamental Design for Stove-Doors, of which the following is a specification, reference being had therein to the accompanying drawings, forming part thereof.

The figure is a perspective view of a stove door, showing our new design.

We claim:

The ornamental design for a stove door, as shown.

JOHN A. ALEXANDER.
FRANK K. BERRY.

Witnesses:

W. J. BELKNAP,
JAMES P. BARRY.
